UNITED STATES PATENT OFFICE.

CLARENCE E. COX, OF FRANKLIN, PENNSYLVANIA, ASSIGNOR TO CHICAGO PNEUMATIC TOOL COMPANY, OF NEW YORK, N. Y., A CORPORATION OF NEW JERSEY.

COMPRESSOR-CONTROLLING APPARATUS.

Application filed May 7, 1924. Serial No. 711,558.

This invention relates to apparatus for controlling the operation of fluid compressors, pumps and the like. It has particular application to the loading and unloading during starting and stopping periods of air compressors arranged for intermittent operation.

Certain types of prime movers used to operate compressors are relatively inefficient under certain conditions, as when starting, when operating at low speeds, or in a cold condition. The electric motor, which is a particularly desirable type of power unit for the intermittent operation of compressors, is characterized by a relatively low starting torque, especially the alternating current motor, and by an inability to carry its load until it has attained its operating speed. Hence when an electric motor forms the driving element efficient and positively operating apparatus for maintaining the compressors in an unloaded condition during the starting and stopping periods is a requisite. Such apparatus is desirable also on installations utilizing an internal combustion engine to drive the compressor.

One of the objects of the invention is to provide simple and reliable apparatus of the described type which will operate in an efficient and positive manner during the starting and stopping periods. Another object is to prevent loading of the compressor in case the driving engine fails to attain its operating speed. Other objects will be apparent from the detailed description which follows.

The invention comprises utilizing a built-up pressure which varies in proportion to and closely approximates in time the variations in speed of the compressor for controlling suitable unloading mechanism on the compressor. It may take advantage of the fact that the fluid pressure developed by a gear type rotary pump is a function of its speed when some throttling effect is produced in the discharge line from the pump. The fluid pressure medium may be from a circulating system associated with the compressor as its cooling or its lubricating system, or from a system specially designed for compressor control.

In order to make clear the nature of the invention and the manner of its operation, concrete embodiments of the genus consti-

tuting the invention are disclosed in the accompanying drawings, in which:

Fig. 1 is a side elevational view of a compressor partly cut away to disclose an unloading valve and showing the control mechanism for the latter in section as on the line 1—1 of Fig. 2;

Fig. 2 is an end elevation view of the parts shown in Fig. 1 with the control mechanism disclosed in section substantially on the line 2—2 of Fig. 1; and

Fig. 3 is a view similar to Fig. 2 showing a modified form of control mechanism.

The invention is disclosed as applied to a compressor of the air cooled type and its lubricating system is selected, merely by way of illustrating the invention and not for limiting it, to provide the fluid pressure medium utilized for the automatic control of the loading and unloading of the compressor. Referring now to the drawings, A is the compressor having fly wheel B, the same being driven by any suitable type of prime mover (not shown), such as an electric motor. The fluid circulating system for lubricating the compressor includes a suitable pump C, preferably of the gear type, connected to the shaft of the compressor by a suitable coupling (not shown), the pump having an inlet connection c leading to the sump or lubricating reservoir a at the base of the compressor and an outlet connection leading to the splash trough a' and if desired to other parts requiring lubrication, this outlet connection comprising two parts, the one c' leading to the casing 4 of the control mechanism later to be described and the other c² from casing 4 to splash trough a'.

The compressor has one or more fluid operated unloading valves D of any suitable or desired type, the one illustrated being the well known plate unloading valve disclosed in U. S. Patent No. 1,275,843 issued August 13, 1918, to William H. Callan. The unloading valve D comprises essentially a cylinder d having a piston d' movable therein in one direction by motive fluid admitted through a pipe connection d² and arranged to actuate the fingered valve lifter d³, for holding the plate valve d⁴ off its apertured seat d⁵, the lifter d³ and the piston d' being returned to inoperative position by a spring d⁶.

The automatic control mechanism for the unloading valve D comprises the casing 4 having a vertically disposed cylindrical bore 5 therein, within which there is arranged for 5 reciprocatory movement a double headed piston 6, the heads 6^a and 6^b of which are connected by a stem 7 and form therebetween a chamber 8 provided with a constantly open outlet port 9 which communicates with the 10 fluid connection d² extending to unloader valve D. Piston head 6^a performs the function of a valve in controlling an inlet port 10 from which a pipe 11 leads to the air receiver (not shown) supplied by the compressor. The piston head 6^b likewise functions 15 as a valve in controlling a vent port 12 leading to atmosphere. The double headed piston or control member 6 is normally retained in its lowermost position as shown in 20 Figs. 1 and 2 by a loading spring 13, one end of which spring is received in a socket in the head 6^b and the other end engages a centering projection on the interior of a range adjusting nut 14 in threaded engagement 25 with the casing 4. The double headed piston 6 has on its lower end a projecting stem 15 adapted to engage the bracket E which supports the casing 4 and closes the lower end of the cylindrical bore 5. There 30 is thus provided in the lower end of bore 5 and below piston head 6^a a chamber to which the lubricant issuing from pump C has access through its outlet pipe c' by means of a horizontal bore 16. Casing 4 above bore 35 16 has a vertical bore 17 joining bore 16 by a reduced opening 18 thereby forming a seat 19 for a check valve in the form of a ball 20 urged toward its seat by a spring 21, the tension of which may be adjusted by a screw 22 threaded into the upper end of bore 17. A washer 23 and lock nut 24 hold screw 22 in adjusted position. A vent 18' leads past check valve 20 into bore 17 to which the second part or section c² of the outlet pipe from 40 pump C connects as shown.

The operation of the apparatus disclosed in Figs. 1 and 2 is as follows: When the compressor is not in operation, the position of the parts is as shown, with air from the receiver acting on the piston d' of the unloading valve D to maintain the inlet valve d⁴ off its seat, the connection being through pipe d², outlet 9, chamber 8 of the control device, inlet 10 and pipe 11 which 45 connects with the air receiver. Thus the compressor is entirely unloaded. When the prime mover for the compressor is started, pump C immediately begins to force oil from the sump a into casing 4, the oil discharged 50 by the pump entering bore 16 and the chamber below the piston head 6^a of the control device and being vented through opening 18' to bore 17 and thence through pipe c² to the splash trough a'. With the development 55 of pressure spring 21 of check valve

20 yields, being of much less resistance than spring 13, and the oil also passes out through restricted opening 18 into bore 17. As the compressor speeds up, the vent 18' and the restricted outlet 18 are unable 70 to take care of the oil discharged by the pump, hence pressure builds up in bore 16 and below piston head 6^a until the tension of the spring 13 is overcome whereupon the double ended piston control member 6 moves upwardly, piston head 6^a closing air inlet 10 and piston head 6^b uncovering vent 12 whereupon the motive fluid which has previously 75 acted on piston d' of the unloader valve D is exhausted, and plate valve d⁴ is thereupon released to function as an inlet valve and the compressor is loaded. In the upward movement of member 6 the end of stem 15 is exposed, thus increasing the area subjected 80 to the pressure of the lubricating system so that member 6 moves quickly and positively to its upper position. Thus control member 6 through its stem 15 has a differential area subjected to the pressure in the lubricant. When the pressure in the lubricating system falls through reduction in compressor speed, 85 spring 13 restores control member 6 to its original position so that chamber 8 is again closed to atmosphere and opened to motive fluid from pipe 11 and unloading valve 90 D is placed in operation.

In Fig. 3 a modified form of control device is shown, the principle of operation, however, being substantially the same. The control device comprises a casing 25 having a large horizontal bore 26, and a smaller vertical bore 27 provided with a reduced extension 28 joining bore 26 and forming a seat for a check valve 29 which has a small vent 28'. Outlet pipe c' connects with reduced bore 28 below check valve 29 and pipe c² with bore 27 above the check valve. Within bore 26 is a piston 30 backed by a loading spring 31 and a vented range adjusting nut 32, these parts closing one end of bore 26. The other end of bore 26 is closed by a casing 33 in threaded engagement therewith. Casing 33 has a horizontal bore 34 at its outer end with a reduced extension 35 coaxial with bore 26 and communicating therewith. Within bore 34 is a valve 36 cooperating with a seat at the entrance to bore 35 and having a reduced stem 37 provided with a cylindrical end 38 fitting bore 35 and arranged to control a vent port 39 and to engage a 10 projection 40 on piston 30 which projection has a bevelled edge which seats in a similarly bevelled socket 41 in casing 33. A spring 42 backed by a closure cap 43 urges valve 36 toward its seat and cylinder 38 into engagement with projection 40, the arrangement being such that when projection 40 is seated in its socket, valve 36 is held off its seat and there is free communication between pipe 11' from the air receiver and pipe 12

d^2 leading to unloader valve D. Projection 40 on piston 30 operates to make the latter a differential piston in the same manner that stem 15 acts in the modification shown in

5 Figs. 1 and 2.

The operation of the modification shown in Fig. 3 will be apparent from the drawing. As the oil pressure builds up against piston 30 and overcomes spring 31, piston 10 30 moves away from the end of casing 33 thus permitting valve 36 to move under the pressure of its spring 42 to seat valve 36 and cut off the connection between pipes 11^a and 15 d^2 . At the same time cylinder 38 functioning as a valve uncovers vent 39 to relieve the unloading valve D and to permit the latter to function as an inlet valve. When the pressure in the lubricating system falls, the parts return to the position shown in 20 Fig. 3.

From the above it will be apparent that both forms of the invention herein disclosed provide simple and positively operated means for maintaining a compressor in unloaded condition when the same is operated at a speed lower than that predetermined by the adjustment of the device, that pressure in a fluid circulating system varying in proportion to and concomitantly with the speed 25 of the compressor is utilized to load the compressor when its speed exceeds the predetermined rate, and that the adjusting means for controlling the tension of the spring acting upon the differential piston subjected to the built-up pressure in the fluid circulating system and of the spring acting on the check 30 valve which controls the time of opening of the check valve and the amount of flow thereby adapt the compressor to use with prime movers having widely varying power characteristics.

Having now described my invention and the manner of its use, what I claim and desire to secure by Letters Patent is:

45 1. In combination, a compressor having a lubricant circulating system operating in proportion to the speed of the compressor including a pump and a chamber into which the pump discharges, a valve yieldably 50 opposing the passage of fluid from said chamber, a restricted by-pass around said valve to permit a circulation of said fluid at all times, a fluid pressure operated unloader for said

compressor, and means responsive to built up pressure of said fluid in said chamber for controlling the admission of motive fluid to said unloader to actuate the same.

2. In combination, a compressor having a liquid circulating system operating in proportion to the speed of the compressor including a pump and a chamber into which the pump discharges, a valve yieldably opposing the passage of liquid from said chamber, means for varying the resistance of said valve to the passage of said liquid, a restricted by-pass around said valve to permit the circulation of said liquid at all times, an unloader for said compressor, and means responsive to the pressure of said liquid in said chamber for controlling said unloader.

3. In combination, a compressor having a liquid circulating system operating in proportion to the speed of the compressor including a pump and a chamber into which the pump discharges, a valve for opposing the passage of liquid from said chamber, a spring arranged to press said valve to its seat, means for adjusting the tension of said spring, an unloader for said compressor, and means responsive to the pressure of said liquid in said chamber for controlling said unloader.

4. A controlling device for compressors having fluid operated unloading means and lubricant circulating systems comprising a casing having a chamber forming a part of the lubricant circulating system, a valve yieldingly controlling the outlet of said chamber to cause the lubricant to build up pressure in said chamber, means for adjustably predetermining the yielding tension on said valve, a restricted by-pass around said valve to insure circulation in said lubricant system at all times, a piston movable in response to the built up pressure in said chamber, adjustable means for yieldingly opposing movement of said piston, and valve means carried by said piston and arranged to connect the unloading means of the compressor either to a source of fluid pressure or to exhaust dependent upon the position of said piston.

Signed by me at Franklin, Penna., this 30th day of April, 1924.

CLARENCE E. COX.
